COMBINED MIRROR AND FLASHLIGHT

Charles R. Bowland, 9 Oakdale Road, Spring Valley, Ill.

Filed Oct. 28, 1964, Ser. No. 82,363

Term of patent 14 years

(Cl. D86—10)

Fig. 3

Fig. 1

Fig. 2

I claim:

The ornamental design for a combined mirror and flashlight, as shown.
